SELF-ALIGNING CONTACT

Fred W. Curtis, Chicago, Ill., assignor to Ivano, Inc., a corporation of Illinois

Application June 30, 1943, Serial No. 492,855

3 Claims. (Cl. 200—166)

This invention relates to a self-aligning contact, and more particularly to an improvement in a circuit breaker element designed for use in the ignition system of an internal combustion engine.

One feature of this invention is that it provides an improved self-aligning element adapted to maintain proper contact relationship with another circuit breaker element; another feature of this invention is that it permits the freedom of movement desirable to maintain good electrical contact with another cooperating contact, while providing an improved electrical conducting path between the movable contact element and its supporting member; yet another feature of this invention is that it obviates difficulty with dirt and moisture between the portions forming the universal mounting; and a further feature of this invention is that it provides a fixed circuit breaker element of reduced dimensions. Other features and advantages of this invention will be apparent from the following specification and the drawing, in which:

Figure 1 is a side elevation of one embodiment of a self-aligning contact unit; Figure 2 is a top plan view of the device shown in Figure 1; Figure 3 is a partial vertical sectional view of such device, along the line 3—3 of Figure 2; Figure 4 is a top plan view of the supporting stud with the contact element and spring removed; and Figure 5 is a horizontal sectional view along the line 5—5 of Figure 3.

Self-aligning points, wherein both contacts have flat surfaces and one of the contact elements has limited universal movement to insure proper contact with the other element, have had considerable commercial success in difficult ignition breaker point applications, as in trucks and other heavy engines. Such points are being manufactured and sold by the assignee of this application in accordance with the disclosure of Janser Patent 2,214,530, of September 10, 1940, and such points have proved highly satisfactory except in a few applications.

Under conditions where there is an excessive amount of dirt and grease on and around the breaker points, and a large amount of moisture, it has been found that occasionally a particle of dirt works in between the interengaging supporting surfaces, which have heretofore been partial spherical surfaces generated about the same center. When this occurs it enables moisture to get between these supporting surfaces and the dirt and moisture cause arcing and contact difficulties between the movable element and its support.

The present invention is an improvement on

5 self-aligning breaker points of the kind shown in the aforementioned Janser patent; and this application is directed entirely to an improved construction and arrangement of the cooperating portions forming a mounting for the movable element. More particularly, the arrangement is such that the convex and concave portions engage each other only over an annular surface, there being a pocket within the confines defined by this engagement wherein dirt and moisture may accumulate; and the arc of the concave portion is reduced, to improve the supporting contact where it is only annular and to reduce the all-over dimensions of the unit.

10 Only one unit of the two cooperating breaker point units is shown in the drawing of the present application, inasmuch as two such units and an operative circuit and an actuating arrangement is illustrated in Figure 1 of the above-mentioned Janser patent, to which reference may be made for a more complete description of the general operation of self-aligning breaker points of the kind here disclosed. Generally, the fixed contact point is carried by the movable breaker arm; and the cooperating unit comprises a supporting stud with a contact element having limited universal movement, means being provided, in the form of a spring ring, for maintaining the movable element in operative relationship with its supporting member.

15 Referring now more particularly to the figures of this application, an upper movable contact member or element is shown as having a body portion 10 and a contact face 11. As may be best seen in Figure 3, the body of this contact member has an external outwardly and downwardly sloping surface 12, which is preferably an annular partial surface of a sphere; and an internal concave portion having a surface 13. The description 20 of the outer surface 12 as sloping outwardly and downwardly is, of course, with reference to the portions shown in the accompanying drawing; and such description is to be construed in accordance with the particular position in which the contact unit may be placed in actual operation. Moreover, while the supporting member is here illustrated as a stud adapted to be screwed into a threaded opening in a plate in the distributor, it may be of any other common type, as for example 25 a rivet adapted to be mounted in the distributor plate or in the breaker arm.

30 In the particular embodiment of the supporting member illustrated in the accompanying drawing, an upwardly extending convex portion 14 is provided. This portion is in the form of a

truncated partial spherical shape, the radius of curvature being the same as that of the concave portion and the centers being concentric when the parts are in operative relation. The truncated arrangement is best shown in Figure 3, where it will be seen that the upper part of the spherical surface is cut off or ground away, so that only an annular external partial spherical surface 15 remains to make engagement with the surface of the concave portion 13. Beneath this convex portion 14, the supporting member is provided with an annular outwardly extending shoulder, and below this shoulder it tapers downwardly and inwardly to provide the external surface 16. Beneath this there may be a conventional hexagonal portion 17 to enable use of a wrench, and a threaded shank portion 18.

In order to maintain the two members in proper and desired relationship during operation while permitting limited universal movement of the contact element 10, a ring 19 of spring metal is provided. This ring encircles a portion of both of said members, its upper part contacting the surface 12 on the movable element 10 and its lower part contacting the surface 16 on the supporting stud. The downwardly and inwardly sloping arrangement of the surface 16 causes the edge of the ring contacting it to always tend to move downwardly, so that the spring action of the ring tends to always urge the two members together; and the fact that the surface 12 is a partial spherical surface about the same center as the two surfaces forming the swivelable support enables easy movement of the contact element 10 within the upper end of the spring. The form of spring ring shown has a solid annular upper portion and lower finger portions. These lower portions are arched, so that both edges of the ring have a lesser diameter than the central part thereof. The separation between the lower finger portions enables a substantial change of diameter of this lower portion without distortion of the metal beyond its elastic limits, so that the ring may be slipped down over the parts during assembly.

Grinding or otherwise removing the upper portion of the convex member 14 leaves a space between it and the cooperating surface of the concave portion 13. In addition, the convex portion is provided with a central depression 20 of substantial size relative to the convex portion. The result is that there is a pocket of substantial size and volume within the confines of the annular engagement between the concave and convex portions. Any hard particles or moisture working in between the annular supporting surfaces tends to keep on working in and to accumulate in the pocket thus provided. Any dirt thus accumulated merely remains in the pocket without creating any difficulties; and moisture therein dries out as soon as the excessively moist conditions no longer exist.

In addition, I have found that where the total contact area between the interengaging supporting portions are in a relatively small annular ring, it is preferable to reduce the arc of the concave portion. In the embodiment here shown this concave portion now only subtends a central spherical angle of about 120°, whereas previous arrangements of this kind have subtended central angles closely approaching 180°. This reduction in the central spherical angle subtended not only reduces wear on the cooperating surface where there is only an annular engagement, by getting the slope further away from the vertical, but also enables a reduction in the over-all height of the contact element, the height from the portion 17 to the contact face 11. This is of considerable advantage in certain applications where space is at a premium.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. Apparatus of the character described, including: a contact member having a body portion and a contact face; a supporting member adapted to engage said body portion to support said contact member for limited universal movement, one of said members having a concave partial spherical portion and the other having a convex portion adapted to be at least partially received by said concave portion, the construction and arrangement being such that said portions make only an annular contact, although one of appreciable width, and such that there is a closed pocket between said portions within the confines of said annular contact; and means for maintaining said members in the desired relationship.

2. Apparatus of the character described, including: a contact member having a body portion and a contact face; a supporting member adapted to engage said body portion to support said contact member for limited universal movement, one of said members having a concave partial spherical portion and the other having a truncated convex partial spherical solid portion having a depression in the center thereof forming a closed pocket of substantial size relative to this portion, the radii of said portions being the same, whereby said portions make only an annular contact, but wherein the annular contact area is of substantial width; and means for maintaining said members in the desired relationship.

3. Apparatus of the character claimed in claim 2, wherein said concave portion subtends a central spherical angle of only about 120°.
